OUTLET FOR HUMIDIFYING DUCTS

Agnew H. Bahnson, Jr., Winston-Salem, N. C.

Application August 9, 1944, Serial No. 548,764

9 Claims. (Cl. 98—40)

1

This invention relates to outlets for humidifying ducts and more particularly to outlets for a "wet duct" humidifier system.

In these systems at least one blower or fan is employed to draw air into a distributing duct and to blow it under pressure through said duct. At least one humidifying device or atomizer is located in the duct, usually adjacent the discharge side of the blower. The compressed and humidified air flows along the duct, which leads through the space to be humidified, and is discharged therefrom at spaced points by means of outlets or discharge nozzles. A wet duct system of this type is described more completely in my Patent No. 2,358,847. The present application in some respects constitutes a continuation-in-part of this acknowledged prior application.

It is essential that all water discharged from the duct be either fully vaporized or in the form of a mist whose particles are so fine that they evaporate quickly in the room air before reaching machinery or goods that might be damaged by water. One condition that may result in damage from water is the tendency of lint to collect in "streamers" at the discharge ends of the outlets and for water to follow along the streamers and to be blown in drops from their outer ends. It is also true that, if the outlets do not make a tight joint where they contact the duct, wet air may be blown out at this point which frequently carries water in the form of drops. The discharge of water at any point in the form of drops is, of course, highly objectionable as it may cause considerable damage to the machinery or the materials in the room.

The practice has been to solder flanged outlets to the outer wall of the duct to prevent the escape of water drops but I have found that a much simpler and less expensive joint construction will afford adequate protection against the blowing of water drops into the room air. Water tending to escape through the joint will be blown along the tapered outlet, and evaporated before it reaches the end of the outlet, when the outlet flange is positioned within the duct and drawn into reasonably tight engagement with the inner surface of the duct by a series of bendable strips that are riveted to the outlet.

Objects of the present invention are to provide duct outlets of simple and inexpensive construction that may be detachably secured in place on a humidifier or air conditioning duct. An object is to provide a wet duct outlet having an outer end construction that precludes the formation of lint streamers. A further object is to provide

2

duct outlets with attached collars at their outlet ends, the collars being shaped to preclude the formation of lint streamers and, preferably, of a standard or uniform size for outlets of different lengths or of different inner end diameters.

These and other objects and advantages of the invention will be apparent from the following specification when taken with the accompanying drawing in which:

- 10 Fig. 1 is a fragmentary plan view of a wet duct humidifier system having outlets embodying the invention;
- 15 Fig. 2 is a perspective view of a flanged outlet collar;
- 15 Fig. 3 is a perspective view of an outlet showing the collar in position thereon;
- 20 Fig. 4 is a fragmentary vertical section through an outlet and adjacent duct structure as seen on the plane indicated by line 4—4 of Fig. 1;
- 20 Fig. 5 is an enlarged section through the lip of an outlet showing diagrammatically the flow of the lint in the outlet; and
- 25 Fig. 6 is a similar enlarged sectional view of a modified outlet lip construction.
- 25 In the drawing, the reference numeral 1 identifies the duct that is supported on an outer wall 2 of the room or mill and has a plurality of outlets 3 for discharging moist air and entrained water mist into the room air. A blower fan 4 on shaft 5 centered in the duct is driven by a belt 6 and motor 7 mounted outside the duct, the shaft 5 being journaled in suitable bearings 8 mounted in a frame 9. The fan draws outside air into inlet end 10 of the duct and means, not shown, may be provided for the recirculation of room air in admixture with or in place of the outside air. The air stream passes through the radial vanes 11 which eliminate the radial component of motion imparted by the fan and then past a humidifying unit 12 that is centrally mounted in the duct by a bracket 13. The humidifier unit may be of the atomizer type or, as illustrated, of the type including a water throwing disk 14 within a casing 15 and mounted on a shaft 16 which carries a pulley 17 driven by the motor 7 through the belt 18. Water fed to the disk 14 is projected against a ring of atomizer teeth, not shown, and converted into a fine mist which is entrained in and evaporated by the air stream. The outlets 3 are spaced along the length of the duct at suitable points to discharge the moisture laden air and entrained water mist into the room.
- 40 The outlets 3 comprise a sleeve portion 19 in the shape of a truncated cone that has an annu-
- 45
- 50
- 55

55 The outlets 3 comprise a sleeve portion 19 in the shape of a truncated cone that has an annu-

lar flange 20 at its rear or inlet end, see Figs. 3 and 4. The outlet is mounted in the air duct by drawing its rear flange against the inner wall of the air duct 1 by straps or clips 21 that are secured to the inner wall of the outlets by rivets 22. Air and water mist that escapes through this joint is projected along the outlet sleeve 19 and no drops of water are blown into the room by the air that escapes through the joints.

The outlet 3 may be a unitary structure, as described hereinafter with reference to Fig. 6, but it is preferable to form the discharge end of the outlet as a detachable split collar 23 having an inner conical flange 24 snugly fitting within the outer end of the outlet sleeve 19. The collar 23 may be rolled or pressed from strip material and, as formed, is of somewhat larger diameter than will fit within the outlet, see Fig. 2. The collar is compressed or collapsed to introduce the flange 24 into the end of sleeve 19, and then allowed to expand into engagement with the sleeve. One edge of the outer flared flange 25 of the collar is extended circumferentially beyond the radial split to provide a locking strip 26 that is bent over the other edge of flange 25 to lock the collar in expanded position within the outlet sleeve, see Figs. 3 and 4.

The axes of the conical sleeves 19 of the outlets 3 are inclined or pitched towards the blower end of the duct to effect a smooth non-turbulent deflection of portions of the main duct air stream through the outlet and into the room along paths substantially normal to the duct axis. The inner flange 24 of the collar is shaped to conform closely to the inner wall of sleeve 19 and therefore has a pitched circumferential portion 27 that merges into a straight or right cylindrical portion 28 at the opposite side of the flange, see Fig. 2.

The collar 23 or discharge end of the outlet is provided with internal circumferential ribs 29, 30 that are axially spaced to leave a circumferential groove 31 in which the air stream sets up an eddy or low velocity region in which lint may collect. The air stream is directed radially inwardly by the approach side of the circumferential rib 29, and water particles, lint and other foreign material that may be entrained in the main body of the air stream are thereby directed away from the flared flange 25 that forms the outer end of the duct outlet. A vent or drain opening 32 is provided at the lower portion of the groove 31 for the escape of water that may collect in the groove. Water escaping through opening 32 is not discharged into the room but is caught by a trough, not shown, that is arranged below the duct and its outlets to carry away condensate or other water that may drip from the duct.

There is an aspiration of room air and formation of an annular eddy current at the concave face of the flaring flange 25 and, with heavy concentrations of lint in the room air, there may be some tendency for lint to deposit from this aspirated air upon the flange 25. This can be eliminated by forming the flaring flange in two sections, see Fig. 6, the inner section 25a being inclined at about 45° and the outer section 25b being inclined at about 65° to 70°. The Fig. 6 embodiment differs in other respects from the construction illustrated in Figs. 1 to 5 as only a single circumferential rib 29' is used and this rib and the flaring flange 25a, 25b are integral with the outlet sleeve 19'. The single rib 29' is sufficient, whether integral with the sleeve 19' or on an attached collar, to prevent the formation of streamers on the flaring flange of the outlet when

the amount of lint in the room air is relatively low.

While I have described what I consider to be the most advantageous embodiments of the invention, it is evident, of course, that various modifications can be made in the structures which have been described without departing from the purview of this invention. Some features of outlet constructions make them advantageous for use in dry duct distribution systems as well as in the wet duct system which has been described. The angle made by the flaring flange at the discharge end of the outlet can be varied rather widely. Various arrangements other than those described may be employed for securing the outlets to the air ducts and, of course, the collars can be mounted at the discharge ends of the outlets in other manners. These and other modifications of the invention which fall within the scope of the following claims will be recognized by those skilled in this art.

I claim:

1. An outlet of the type described which comprises a sleeve having the general shape of a truncated cone having one substantially straight side and an opposite side tapered towards the outlet, a flaring flange at the inlet end of said sleeve and a collar mounted at the discharge end of said sleeve, said collar having an outwardly flaring flange and an inwardly extending annular rib circling the outlet adjacent said flange and forming the most constricted point of said outlet.

2. An outlet as recited in claim 1 wherein the said tapered side makes an angle of from about 15° to 25° with the axis of said sleeve.

3. An outlet as recited in claim 1 wherein the outwardly flaring flange on said collar makes an angle of from about 50° to 90° with the axis of the outlet.

4. An outlet as recited in claim 1 wherein a second inwardly extending annular rib is provided at an axially spaced short distance to the rear of said first rib, leaving a channel therebetween.

5. An outlet as recited in claim 1 wherein said outwardly flaring flange comprises two sections at different inclinations to the axis of the outlet.

6. An outlet for the discharge of air from a humidifying duct, said outlet comprising an unobstructed tapered sleeve adapted to be secured at its larger end in an opening in the wall of the duct, a split collar detachably secured to the smaller end of said sleeve, said collar comprising a rearwardly and outwardly flaring flange fitting the inner surface of said sleeve at the smaller end thereof and a forwardly and outwardly flaring flange extending forwardly from the smaller end of said sleeve.

7. An outlet for the discharge of air from a humidifying duct, said outlet comprising a sleeve mounted in an opening in the side wall of said duct and extending laterally therefrom, said sleeve having a relatively long internally unobstructed body portion which is tapered toward the discharge end thereof, a relatively short flange extending forwardly and outwardly from adjacent the discharge end of said body portion and an annular rib extending inwardly beyond the edge of the discharge end of said body portion and forming the most constricted point of the outlet connecting the discharge end of said body portion with said flange.

8. An outlet for the discharge of air from a humidifying duct, said outlet comprising a sleeve mounted in an opening in the side wall of said duct and extending laterally therefrom, said

sleeve having a relatively long internally unobstructed body portion which is tapered toward the discharge end thereof, a relatively short flange extending forwardly and outwardly from adjacent the discharge end of said body portion and two inwardly extending annular ribs and an intermediate outwardly extending annular rib connecting the discharge end of said body portion with said flange.

9. An outlet for the discharge of air from a 10 humidifying duct, said outlet comprising a sleeve mounted in an opening in the side wall of said duct and extending laterally therefrom, said sleeve having a relatively long internally unobstructed body portion which is tapered toward the discharge end thereof, a relatively short flange extending forwardly and outwardly from adjacent the discharge end of said body portion, a rearwardly and outwardly flaring flange at the inlet end of said body portion adapted to engage the inner wall of the duct around said opening and clips secured to said last named flange and adapted to be bent over the edge of the wall of the duct surrounding said opening to secure the outlet in said opening.
